UNITED STATES PATENT OFFICE.

FRANCIS E. BENTON, OF STOUGHTON, MASSACHUSETTS.

SHOE-LAST.

SPECIFICATION forming part of Letters Patent No. 687,176, dated November 19, 1901.

Application filed May 2, 1901. Serial No. 58,485. (No model.)

To all whom it may concern:

Be it known that I, FRANCIS E. BENTON, a resident of Stoughton, in the county of Norfolk and State of Massachusetts, have invented certain new and useful Improvements in Shoe-Lasts; and I do hereby declare the following to be a full, clear, and exact description of the invention, such as will enable others skilled in the art to which it appertains to make and use the same.

My invention relates to an improvement in shoe-lasts, and more particularly to thimbles for shoe-lasts, the object of the invention being to provide an improved device of this character which will prevent possibility of splitting or otherwise injuring the last when pressure is applied thereon.

A further object is to provide an improved thimble which will be effectually held in the last and cushion blows or pressure thereon.

With these objects in view the invention consists in certain novel features of construction and combinations and arrangements of parts, as will be more fully hereinafter described, and pointed out in the claims.

In the accompanying drawings, Figure 1 is a view in section illustrating my improvements. Fig. 2 is a view of the thimble removed, and Fig. 3 is a view of the locking-collar.

1 represents a last of ordinary construction composed of wood or other material and preferably provided through the heel portion thereof with a transversely-disposed bolt or 35 strengthening-rod 2, as shown. A socket is bored or otherwise formed in the last to receive my improved thimble 3, which is formed preferably from an oblong rectangular spring-metal blank bent into a tube by punching the blank centrally between its ends, the respective ends of the blank being bent into semicircular shape in cross-section, the transverse central portion thereof forming the closed end of the tube, and the lower closed 40 wall thereof extending considerably above the bottom, as clearly shown. The end portion of the blank, or, in other words, the split side sections of the tube, form spring members 5, having slight lateral movement with 45 relation to each other and made with a peripheral groove 6 near their upper ends. To the bottom 4 a flexible washer or disk 7 is se-

cured by a rivet 8, as shown. More than one washer may, if desired, be provided, they being constructed of rubber or other flexible 55 and elastic material, and may, instead of being secured to the thimble, be loosely disposed between the end of the thimble and the socket in the last to cushion any blow or pressure on the last, as will be hereinafter explained.

In the upper portion of the pocket my improved locking-collar 9 is located and comprises a plate 10, secured to the upper face of the last by screws 11, as shown, and an integral sleeve projecting into the socket and bent inward at its lower end, forming an internal flange 12 to spring into the groove 6 in the thimble and securely hold the same in the socket, preventing any possibility of its 70 accidental removal.

With the devices heretofore known and the present machine methods now in vogue where great pressure is exerted on the last, especially on the heel portion thereof in heeling the shoe, 75 the thimble is liable to and, in fact, is split or driven into the last and splits or otherwise injures or destroys the same, and the thimbles are liable to be pulled out of the last when the latter is removed from its support, and 80 to avoid these defects of the devices now in use my invention was devised, and its operation is as follows: When the last is in position to receive the heel and the necessarily great pressure or sudden shock applied there- 85 to, the washers or disks 7 are contracted or yield slightly to compensate therefor and take up the shock, thereby preventing the last from splitting or being otherwise injured, and this cushioning effect of the washers not 90 only lengthens the life of the last, but improves the effectiveness of the same in the manufacture of shoes. The locking-collar 9 being provided with the internal flange 12, located in the peripheral groove 6 in the 95 thimble, prevents possibility of the withdrawal of the thimble until desired. It will also be seen that by making the thimble, as above described, with the slits terminating a considerable distance above the closed bottom a 100 great strength is given to the closed end, as the closed portion of the side wall serves to take a great portion of the strain from the end and prevents splitting the thimble should

excessive and sudden pressure be applied to the last.

Instead of making the thimble split, as shown, it may be made solid in any desired manner, and various other slight changes might be resorted to in the general form and arrangement of the several parts described without departing from the spirit and scope of my invention, and hence I would have it understood that I do not wish to limit myself to the precise details set forth, but consider myself at liberty to make such slight changes and alterations as fairly fall within the spirit and scope of my invention.

Having fully described my invention, what I claim as new, and desire to secure by Letters Patent, is—

1. The combination with a last having a socket therein, of a split tube located in said socket and having a closed lower end parallel with the bottom of said socket, and a cushion riveted to said bottom of the tube and resting upon the bottom of the socket.

2. The combination with a last having a

socket therein and a rod passing transversely through the last and across the lower end of the socket in the last, of a sheet-metal thimble inserted in said socket and having a flat lower end, and a cushion secured to the flat lower end of the thimble and resting on said transverse rod.

3. The combination with a last having a socket therein, of a thimble in said socket comprising a split tube closed at its inner end, and having a peripheral groove near its outer end, a flexible washer secured to the inner end of the tube and a locking-collar comprising a plate secured to the last, a sleeve thereon projecting into the socket in the last and an internal flange on the sleeve located in the groove in the thimble.

In testimony whereof I have signed this specification in the presence of two subscribing witnesses.

FRANCIS E. BENTON.
